(57) **CLAIM**

I claim the ornamental design for a dial for a headlamp, headlamp battery compartment, or the like, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a dial for a headlamp, headlamp battery compartment, or the like according to my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is another perspective view thereof, shown attached to the band of a headlamp;

FIG. 9 is another right side elevation view thereof, shown attached to the band of a headlamp;

FIG. 10 is another left side elevation view thereof, shown attached to the band of a headlamp;

FIG. 11 is another rear elevation view thereof, shown attached to the band of a headlamp;

FIG. 12 is another front elevation view thereof, shown attached to the band of a headlamp;

FIG. 13 is another top plan view thereof, shown attached to the band of a headlamp;

FIG. 14 is another bottom plan view thereof, shown attached to the band of a headlamp.

FIG. 15 is a perspective view of another embodiment of a dial for a headlamp, headlamp battery compartment, or the like according to my new design;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof; and,

FIG. 21 is a bottom plan view thereof.

The broken lines shown in the drawings illustrate environment features and form no part of the claimed design.
